DESIGN FOR A RAIL BENDER

Ian D. Marsh, Belleville, Ill.

Application May 24, 1937, Serial No. 69,517

Term of patent 14 years

To all whom it may concern:

Be it known that I, Ian D. Marsh, a citizen of the United States, residing at Belleville, county of St. Clair, State of Illinois, have invented a new, original, and ornamental Design for a Rail Bender, of which the following is a specification, reference being had to the accompanying drawing, forming a part thereof, in which—

Fig. 1 is a plan view of a rail bender showing the top of my new design.

Fig. 2 is an end elevation looking toward the left-hand end of the rail bender as shown in Fig. 1.

Fig. 3 is an end elevation looking toward the lower end of the rail bender as shown in Fig. 1.

I claim:

The ornamental design for a rail bender as shown.

IAN D. MARSH
